UNITED STATES PATENT OFFICE

2,494,805

OPERATING BAR FOR VENDING MACHINES.

Christian Gabrielsen, Whippany, N. J., assignor
to The Rowe Manufacturing Co., Inc., Whippany, N. J., a corporation of New York

Application December 27, 1946, Serial No. 718,680.

3 Claims. (CL 194—1)

1

My invention relates to an improved operating bar for vending machines and more particularly coin controlled vending machines.

Most vending machines are adapted to dispense one of a plurality of different brands of merchandise selected by the purchaser. The different brands are usually stacked in adjacent columns which are presented for the purchaser's choice. Upon the deposit of coins of the correct denomination, representing the value of the merchandise to be sold, the machine is placed in operative condition so that when a purchaser selects the particular brand desired, he may actuate an operating plunger which then dispenses the merchandise.

A coin controlled vending machine adapted to vend articles, such as cigarettes, is shown in Rowe et al. Patent 2,231,952, dated February 19, 1941. In the vending machine there shown a plurality of operating plungers are locked by the coin controlled mechanism through a common locking bar having pinions at each end thereof. The locking bar is supported by a pair of rods which serve to hold the pinions in engagement with stationary racks at each end of the bar.

In the construction there shown the friction of the pinion bar along the supporting rods 40 interferes with the smooth operation of the vending machine. Furthermore, upon the operation of one of the plungers remote from the locked end of the bar, the torque round an axis at right angles to the longitudinal axis of the bar is such that excessive strain and wear occurs between the pinion and rack teeth. This torque in addition increases the friction tending to jam the operating bar especially when wear takes place in the pinion teeth or the rack teeth. Then, too, in order to maintain parallel motion of the pinion bar in the construction shown in the Rowe et al. Patent 2,231,952, the pinion bar must rotate. The force causing the bar to rotate is the force with which a plunger is pulled times the lever arm between the contact point of the pinion teeth and the axis of the pinion bar. It will be observed that this lever arm in Rowe et al. patent is an extremely small one thus serving to make the machine difficult to operate.

One object of my invention is to provide an improved operating bar adapted to be locked at one end and to control the operation of a plurality of operating plungers adapted to vend different brands of merchandise at a purchaser's selection.

Another object of my invention is to provide

2

an operating bar which will reduce the force necessary to actuate the vending machine.

Another object of my invention is to provide an operating bar of improved construction in which friction is reduced to a minimum.

A further object of my invention is to provide an operating bar which is sturdy, trouble-free and in which the disadvantages of the prior art construction are eliminated.

10 Other and further objects of my invention will appear from the following description.

In the accompanying drawings, which form part of the instant specification and which are to be read in conjunction therewith and in which like reference numerals are used to indicate like parts in the various views:

Figure 1 is a perspective view of a coin controlled vending machine with parts broken away showing my improved operating bar.

20 Figure 2 is a sectional view with parts eliminated taken along the line 2—2 of Figure 1.

Figure 3 is a fragmentary sectional view taken on the line 3—3 of Figure 2.

Referring now to the drawings, the vending machine shown is adapted to vend articles such as packages of cigarettes of various brands normally stacked in columns held in a plurality of adjacent containers or chutes 2. A corresponding plurality of operating plungers 4 are adapted to dispense the articles to be vended as, for example, cigarettes, from the chutes or columns

30 2 through operating handles 6. Each operating plunger 4 carries a downwardly extending projection 8 which engages the rear portion of the operating bar 10. One end 12 of the operating bar 10 is normally locked through a coin controlled lock mechanism (not shown) which forms no part of the instant invention. The lever 14 is a portion of the coin controlled locking mechanism.

35 40 Upon the insertion of coins of the proper denomination, the locking mechanism is placed in inoperative position so that the end 12 of the operating bar 10 is free to move to the left as viewed in Figure 1. Rigidly secured to the rod or bar 10 which is circular in cross-section, are a pair of toothed segments 16 and 18. The segments are secured to the bar inwardly of the ends thereof as can readily be seen by reference to Figures 1 and 2. Secured to the machine

50 housing 20, in any suitable manner, are a pair of plates 22 and 24 provided with slots 26 and 28 in which the ends of the bar 10, projecting beyond the segments 16 and 18, are lodged. Supported from the framework in any appropriate manner, I provide a pair of racks 30 and 32

45 55

50 55

adapted to engage the teeth 34 and 36 formed upon the segments 16 and 18.

In operation, when the end 12 of the operating bar is freed by the insertion of coins of the proper denomination into the coin controlled mechanism, a purchaser may pull one of the operating handles 6 depending upon the particular brand desired. Pulling the handle 6 pulls the plunger 4 and its projection 8 thus moving the operating bar forwardly. Since the segments 16 and 18 are rigidly secured to the bar 10, the forward motion of the bar by force applied at any point throughout its length will move the upper portion of the segments forwardly. The lower portions of the segments, however, are formed with teeth which are engaged with the racks 30 and 32. This produces a rotation of the bar causing both segments to rotate carrying both ends of the bar forwardly at the same rate. If, for example, the left-hand plunger is pulled, the rotation of the segment 16 will produce rotation of the bar 10 and hence a rotation of the segment 18 insuring that the right-hand side of the bar moves at the same rate as the left-hand side of the bar thus producing a parallel motion of the bar. It will be observed further, that the dimension between the axis of the bar 10 and the teeth of the racks 30 and 32 is many times the diameter of the bar 10. This dimension in my improvement is made so large that the angle subtended by the gear segment is 90° or less. In other words, the dimension is sufficiently large that the operating or locking bar 10 will move the required distance to permit the dispensing action to occur without rotating more than 90°. The lever arm, therefore, through which the force exerted by plunger 4 acts to rotate the bar 10, is large, giving ample mechanical advantage for friction-reduced, easy and smooth operation. The weight of the bar 10 is supported upon the racks 30 and 32 through the segments 16 and 18. The guide slots 26 and 28 in the plates 22 and 24 serve to hold the segment teeth and the rack teeth in engagement.

It will be seen that I have accomplished the objects of my invention. I have provided an improved operating bar adapted to be locked at one end to control the operation of a plurality of separate operating plungers. My improved operat-

ing bar reduces the force necessary to actuate the vending machine and at the same time reduces friction to a minimum. My improved operating bar is sturdy, trouble-free and eliminates the disadvantages of the prior art.

It will be clear that various changes may be made in details within the scope of my claims without departing from the spirit of my invention. It is therefore understood that my invention is not to be limited to the specific details shown and described.

Having thus described my invention, I claim:

1. In a coin-controlled vending machine having a plurality of operating members selectively movable to dispense articles of a corresponding plurality of containers, a common locking bar positioned to control the movement of each of said operating members, coin-controlled means for immobilizing the locking bar at one point therealong and adapted to free the bar for movement in response to a deposit of a coin, the improvement comprising in combination a pair of racks, a pair of gear segments secured to the bar for movement therewith engaging and supported by said racks, said segments subtending an angle of not more than 90 degrees and means for holding the said segments and racks in engagement.
2. A coin-controlled vending machine as in claim 1 in which the coin-controlled means is attached to the locking bar at one end thereof.
3. A coin-controlled vending machine as in claim 1 in which said means for holding said segments and racks in engagement comprises a pair of plates formed with guide slots extending parallel to said racks, said operating bar passing through said slots.

CHRISTIAN GABRIELSEN.
